BABY'S NURSING BOTTLE OR SIMILAR
ARTICLE

Louis A. Dvonch, Chicago, Ill.

Application September 19, 1950, Serial No. 12,251

Term of patent 14 years

(Cl. D83—8)

To all whom it may concern:

Be it known that I, Louis A. Dvonch, a citizen of the United States, and residing in the city of Chicago, county of Cook, and State of Illinois, have invented a new, original, and ornamental Design for a Baby's Nursing Bottle or Similar Article of which the following is the specification, reference being had to the accompanying drawings, forming a part thereof.

In the drawings:

Fig. 1 is a front elevation of a baby's nursing bottle or similar article, showing my new design.

Fig. 2 is a side elevational view thereof.

Fig. 3 is an elevational view looking at the rear and normally lower side of my new feeding bottle.

Fig. 4 is a top plan view thereof.

I claim:

The ornamental design for a baby's nursing bottle or similar article, substantially as shown.

LOUIS A. DVONCH.
